UNITED STATES PATENT OFFICE

2,354,994

DRAINAGE INTAKE

Henry Holland, deceased, late of Cleveland, Ohio,
by George W. Holland, administrator, Lake-
wood, Ohio

Application September 22, 1941, Serial No. 411,853

6 Claims. (Cl. 94—33)

This invention, as indicated, relates to a drainage intake. More particularly, it comprises means cooperating with or forming part of a catch basin or similar outlet for surface water diverted from roadways and the like.

The invention embodies some of the features set forth in prior United States Patent No. 2,117,887, issued May 17, 1938, but includes other structural features making such devices more readily applicable to concrete roadways and the like, and providing minimum interference with the smoothness and continuity of the traffic surface. The invention may be formed as an integral structure with the roadway, or may be formed as a pre-fabricated unit for installation at the required points along the roadway. The structure is especially adapted for steep inclines and hillside drainage, and provides ribs and channels positioned angularly from the curb toward the drainage flow as right-hand and left-hand structures, respectively, on opposite sides of the roadway. These ribs and channels cause angular diversions of the drainage flowing thereover with its debris and foreign matter from the surface along the road margins against the curb and into the drainage intakes, respectively. Through the use of suitable reinforcement and quality of plastic material the structure may be formed to function throughout the life of the roadway without the necessity of replacement or repair.

The principal object of the present invention is to provide an economical drainage intake to divert surface water and debris from the roadway in an efficient and dependable manner so that there will be practically no interference with traffic even when the device is operating under heavy duty conditions.

Another object of the invention is to provide a drainage intake structure of a self-cleaning character peculiarly adapted for use on inclined roadways and as right-hand and left-hand structures which will present a traffic surface substantially uniform with the remainder of the roadway and act effectively to divert angularly surface water and miscellaneous matter, such as leaves, twigs, and debris of various kinds into the drainage opening whether under conditions of light or heavy duty service.

Another object of the invention is to provide a drainage intake device which may be prefabricated for use along a roadway and set into place so as to conform to the road surface and have long service life and effective drainage action with substantially no interference with traffic.

Another object of the invention is to provide a

drainage intake unit formed for installation on hillsides and the like so as to act with high capacity efficiency during heavy downpours and to free the roadway of surface water and debris with a high degree of effectiveness and substantially no interference with traffic.

A further object of the invention is to provide a structure formed of reinforced concrete and providing self-cleaning drainage areas over the surface thereof and having high capacity to withstand heavy duty traffic conditions over a long period of service.

Other and further objects of the invention will appear in the course of the following description.

To the accomplishment of the foregoing and related ends, said invention, then consists of the means hereinafter fully described and particularly pointed out in the claims, the annexed drawing and the following description setting forth in detail certain structures embodying the invention, such disclosed means constituting, however, but several of various forms in which the principle of the invention may be used.

In said annexed drawing:

Fig. 1 is a perspective view, partly in section, showing a roadway pavement having a drainage intake unit therein embodying the principles of the invention;

Fig. 2 is a transverse sectional view taken along the line 2—2 shown in Figure 1 looking in the direction of the arrows;

Fig. 3 is a perspective view, partly in section, showing a prefabricated drainage unit embodying the principles of the invention;

Fig. 4 is a view similar to Figure 1 showing a modified form of structure embodying the principles of the invention;

Fig. 5 is a view similar to Figure 1 showing another modified form of structure embodying the principles of the invention as incorporated in the surface of the roadway;

Fig. 6 is a mold board form utilized in producing the drainage surface illustrated in Figure 5; and

Fig. 7 is a top plan view of the structure shown in Fig. 4.

As is clearly shown in Figure 1 of the drawing a prefabricated drainage unit 1 is set into the material of the roadway 2 adjacent the drainage aperture 3 of a curb plate 4 forming part of the marginal curb structure 5 of the roadway.

The drainage unit 1 may be formed of any suitable material, such as cast iron or other metal, or of plastics or material of other character adapted to withstand heavy vehicular traffic.

The drainage unit is preferably a rhombohedral block modified as to its upper surface so as to provide angular ribs 6 intermediate a series of channels 1. The upper surfaces of the ribs are preferably of the full height of the block so as to form a substantially uniform roadway level support for vehicle wheels passing thereover. Through the maintenance of an even travel surface closely adjacent the curb areas of the roadway the traffic hazards caused by vehicles turning away from the curb at each drainage intake to avoid shock to the vehicle occasioned by the conventional depressed form of drainage intake, is entirely avoided and high speed traffic can thus be maintained over the full width of the roadway and with small clearance from the curb margin. It will be noted that the channel ways intermediate the ribs increase in width and depth in a direction toward the drainage aperture and that this construction increases the rate of flow of surface waters into the drainage aperture and exerts lifting power against any debris which may be carried with such surface water. The drainage intake unit therefore is self-cleaning in character and prevents the accumulation of massed debris adjacent the drainage aperture. In order to further enhance the action of the ribs and recesses on the upper surface of the drainage intake unit the ribs are preferably given a specialized form as shown more particularly in Figure 2 wherein inclined surfaces 11 closely approaching the perpendicular at their upper free edges are provided on the sides of the rib toward which the surface drainage flow is directed. The surfaces 11 merge with substantially semi-circular areas 12 at the bottom of each of the channels. On the sides of the ribs opposite the surface 11 curved surfaces 13 are provided, such surfaces preferably being formed on a short radius and tending to cause forceful impact of the surface waters against the substantially perpendicular surfaces 11 of said unit heretofore described. The outer ends of the channels 14 preferably merge with the flat outer marginal top surface 15 of the drainage intake unit and thus avoid the formation of sharp edges through any fracture of the wall areas adjacent the channels.

As has been above stated the drainage intake unit may be formed of metal or of plastic or other material in accordance with requirements of the particular locality where the same are used. In the form of construction shown in Figure 3 the drainage intake unit 16 is formed of a precast block of concrete preferably having reinforcement in the form of transverse bars 17 extending in the direction of the roadway and preferably projecting a substantial distance outwardly from each side face of such precast unit. Additional bars extending longitudinally of the drainage intake unit and transversely of the roadway are preferably provided. Such bars may be in the form of an upper and lower series, the bars 18 of the upper series being embedded centrally of the rib portions of the block, and the bars 19 of the lower series occupying intermediate or offset positions from the bars of the upper series. The ribs and channels on the upper surface of the drainage unit 16 are preferably similar in shape to those heretofore described in connection with Figures 1 and 2 and have been given similar reference characters, and the block and ribs extend at an uphill angle.

In order to take care of exceptionally heavy high speed drainage flow on roadways of steep inclination it is found desirable to increase the

size of the drainage intake unit so as to meet the flow of surface water and direct it toward the curb line a short distance above the drainage aperture and thus prevent the momentum of heavy flow of surface water carrying it past the drainage aperture. A construction of this character is illustrated in Figures 4 and 7 wherein the drainage intake unit 21 is similar in its features to the unit 1 shown in Figure 1, as described above, but in place of having its ribs restricted to the area in front of the drainage aperture 22 has additional ribs 23 with intermediate channels 24 which do not discharge into the drainage aperture but accumulate the surface water in greater volume along the curb so that the full height of the drainage aperture 22 will be utilized in receiving the surface drainage and so that no residual water will pass down the inclined roadway beyond the drainage aperture 22. The block and ribs all extend at an uphill angle and a marginal channel 25 may be provided adjacent the curb above the drainage intake to assist the additional ribs and channels in directing the drainage flow toward the curb and into the drainage intake.

In each of the drainage intake units the ribs and channels are preferably directed angularly in an "uphill" direction to meet the volume of drainage flow and divert such flow into the intake aperture. The degree of such angular positioning of the ribs and channels may be varied in accordance with the volume of flow and the steepness of the roadway over which the surface water passes. It should be pointed out that such inclination of the ribs and channels is an important factor in causing rapid flushing of all debris carried with or floating on the surface water into the drainage aperture. It is to be understood that the length of the drainage aperture will be increased where the volume of surface water on the hillside is larger than that met with on the average roadway.

While precast drainage units formed of cast iron or other rigid material, or of concrete blocks or the like having suitable reinforcement throughout the body of the block and within the ribs, if desired, provide for uniformity of the drainage installations along a section of roadway, there are many instances wherein the roadway itself while in course of construction can be formed with a series of ribs and channels to take care of the flow of surface water into the drainage aperture. A construction of this type is illustrated in Figure 5 wherein the roadway 31 adjacent the drainage aperture 32 is formed with ribs 33 and channels 34, all preferably inclined upwardly across the line of drainage flow as indicated by the arrow, and all having preferably a cross-sectional contour or ribs and recesses corresponding to those shown in Figure 2. In order to provide such integral ribs and channels a mold board 35 of the form illustrated in Figure 6 is provided, such mold board having a series of projections 36 of the contour and outline of the channels and thus forming intermediate the same the rib areas 33 heretofore described.

Other modes of applying the principle of this invention may be employed instead of those explained, change being made as regards the structure herein disclosed, provided the means stated by any of the following claims or the equivalent of such stated means be employed.

It is therefore particularly pointed out and distinctly claimed as the invention:

1. A drainage intake member adapted to be

embodied as a traffic supporting structure in a roadway surface adjacent to and extending in an uphill direction above a drainage aperture in the curb and providing a plurality of ribs and channels which discharge into the drainage aperture and above the same and are directed outwardly from the curb and inclined across the drainage flow in an uphill direction, said channels flared upwardly and being of progressively decreasing width and depth in a direction away from said curb and merging with the roadway surface, and each channel having a substantially perpendicular wall surface against which the drainage flow is directed.

2. A drainage intake member adapted to be embodied as a traffic supporting structure in a roadway surface adjacent to and extending in an uphill direction above a drainage aperture in the curb and providing a plurality of ribs and channels which discharge into the drainage aperture and above the same and are directed outwardly from the curb and inclined across the drainage flow in an uphill direction, said channels flared upwardly and being of progressively decreasing width and depth in a direction away from said curb and merging with the roadway surface, each channel having a substantially perpendicular wall surface against which the drainage flow is directed, and having the opposite wall surface of curved cross-section to cause non-turbulent flow against the perpendicular wall areas.

3. A drainage intake member adapted to be formed as a precast unit for installation on heavy grades of roadways adjacent drainage apertures in the curb margins, and providing a rhomboidal plate, a plurality of parallel ribs and channels on the upper surface of said plate, with said ribs at the level of the plate margins and road surface and said channels of increasing width and depth in an inclined direction toward the intake opening from a point of origin even with the top surface and spaced from the outer margin of said plate, and a marginal channel with cross-channels feeding thereinto, positioned on the up-grade side immediately above the drainage aperture.

4. A drainage intake member adapted to be formed as a precast unit for installation on heavy

grades of roadways adjacent to and extending in an uphill direction above the drainage apertures in the curb margins, and providing a rhomboidal plate, a plurality of parallel ribs and channels on the upper surface of said plate, with said ribs at the level of the plate margins and road surface and said channels of increasing width and depth in an inclined direction toward the intake opening from a point of origin even with the top surface and spaced from the outer margin of said plate, and each channel having a substantially perpendicular wall surface against which the drainage flow is directed.

5. A drainage intake member adapted to be formed as a precast unit for installation on heavy grades of roadways adjacent to and extending in an uphill direction above the drainage apertures in the curb margins, and providing a rhomboidal plate, a plurality of parallel ribs and channels on the upper surface of said plate, with said ribs at the level of the plate margins and road surface and said channels of increasing width and depth in an inclined direction toward the intake opening from a point of origin even with the top surface and spaced from the outer margin of said plate, each channel having a substantially perpendicular wall surface against which the drainage flow is directed, and having the opposite wall surface of curved cross-section to cause non-turbulent flow against the perpendicular wall areas.

6. A drainage intake member adapted for integral engagement in the traffic surfaces on steep roadways comprising a precast rhomboidal block having the upper surface thereof provided with inclined parallel ribs and channels, each of said channels starting from a point spaced from the outer edge of said block and even with the top surface thereof and of increasing width and depth toward the discharge margin of said block adjacent an intake aperture at the side of the roadway, and a marginal channel with cross-channels feeding thereinto, positioned on the up-grade side immediately above the drainage aperture.
